UNITED STATES PATENT OFFICE.

FRANK A. WEEKS, OF PLAINFIELD, NEW JERSEY, ASSIGNOR TO EDWARD KIMPTON COMPANY, OF NEW YORK, N. Y., A CORPORATION OF NEW YORK.

PAPER DRINKING-CUP.

1,002,346.

Specification of Letters Patent. Patented Sept. 5, 1911.

Application filed September 21, 1910. Serial No. 582,977.

To all whom it may concern:

Be it known that I, FRANK A. WEEKS, a citizen of the United States, and a resident of Plainfield, in the county of Union and State of New Jersey, have invented certain new and useful Improvements in Paper Drinking-Cups, of which the following is a specification.

The invention relates to improvements in paper drinking cups, and it consists in the novel features and structure hereinafter described, and particularly pointed out in the claim.

The object of my invention is to produce an efficient paper drinking cup of such inexpensive nature that it may be used once and thrown away, or repeatedly used if desired, and which may lie flat when not in use so that it may be carried in the pocket or a pocket-book and readily opened outwardly when it is to be used.

Among the principal purposes of the present invention is to produce a paper drinking cup of the character described which will be less liable to leakage than those heretofore known and also (which is one of the more essential features of the invention) enabled to stand on its bottom while holding or receiving a liquid, and also when empty. It is intended that the paper drinking cup of my invention may lie flat or in a collapsed condition while in stock in stores or when carried by persons desiring to use the same, and that when the cup is placed in use it will be capable of standing on its bottom, which is a feature which has not heretofore been possessed by flexible paper drinking cups so far as I am aware. Paper drinking cups have heretofore been constructed, but those cups of flexible nature intended to be folded into small compass, have not been capable of standing on their bottom, but on the contrary it has been necessary to hold them in the hand during their use. The cup of my invention may be filled with a liquid and allowed to stand on a table or the like an indefinite length of time or so long as any portion of the liquid may remain unconsumed and within the cup.

The invention will be fully understood from the detailed description hereinafter presented, reference being had to the accompanying drawings, in which:

Figure 1 is a perspective view of a paper

drinking cup constructed in accordance with and embodying my invention, the cup being shown in its expanded condition ready for use; Fig. 2 is a top view of the same; Fig. 3 is a vertical sectional view, partly broken away, through the cup while in its collapsed or flat condition, the section being on the dotted line 3-3 of Fig. 4; Fig. 4 is a vertical section through the cup while in its folded or collapsed condition, the section being taken on the dotted line 4-4 of Fig. 3; Fig. 5 is a vertical central section, on the dotted line 5-5 of Fig. 6, of the cup when in its expanded condition ready for use, and Fig. 6 is a corresponding section through the cup on the dotted line 6-6 of Fig. 5.

I construct the cup shown in the drawings from two pieces of paper of waterproof character, one of said pieces being a blank cut to form when folded over and creased at its middle line 10 the two opposite sides 11, 12 of the cup, and the other piece a strip 13 transversely encompassing the lower portion of the cup and at its upper edges secured thereto by paste, waterproof paste being preferably employed. The piece or strip 13 may be of ornamental character if desired or scalloped along its upper edges. The sides 11, 12 substantially correspond with each other, except that the side 11 at its perpendicular edges is formed with lips 14 which lap upon and are pasted to the corresponding edges of the side 12, as shown in Figs. 1 and 2. The sides 11, 12 are integral at their middle fold-line or crease 10 and hence when the edge-lips 14 of the side 11 are pasted to the edges of the side 12 a flat receptacle is formed which may be bulged or opened outwardly above its lower end to hold a liquid and constitute a drinking cup. In Figs. 1 and 2 I illustrate the sides 11, 12 as bulged outwardly from each other, while in Fig. 4 the cup is shown in its initial flat or collapsed condition with the sides 11, 12 parallel with and close to each other.

One objection to the cup so far as the same has been hereinbefore described is that the sharp wedge-like bottom represented by the crease-line or fold 10 will not permit the cup to stand upon a table or other support, with the result that the cup when containing liquid must be manually held until all the liquid has been consumed or the cup other-

wise emptied, and this objection I remedy by the provision of the lower encompassing strip or band 13, which will lie flat against the sides 11, 12 when said sides are collapsed or pressed together, as shown in Fig. 4, and expand outwardly when said sides are opened outwardly, said band 13 when expanded outwardly affording a support for the cup, as shown in Figs. 5 and 6, enabling it to stand upon a table or the like. The sides 11, 12 when expanded or bulged outwardly naturally take the form of an ellipse, as shown in Fig. 2, and converge downwardly toward the fold-line or crease 10, and to effect the proper expansion of the band 13 and the setting of the same in its expanded condition, so as to support the cup, I initially give the fold-line or crease 10 a slight crease or indentation at and transversely of its center and exert a light pressure, between the finger and thumb, against the opposite edges of the lower part of the cup or the band 13, this pressure having the effect of expanding the opposite sides of the band 13 outwardly, to afford a proper support, and of causing the fold 10 to yield upwardly at its middle on a line transversely of its length and at right angles to the sides of the cup, as at 15 in Figs. 2, 5 and 6, thereby forming a horizontal brace crossing the long axis of the ellipse defined by the cup and serving to maintain the band 13 in its expanded condition, said band being thereby enabled to remain in condition to act as a support for the cup whether the latter be full or empty. The fact that the band 13 is secured at its upper edge only enables the bottom of the cup proper at the transverse middle of the fold-line or crease 10 to yield upwardly, as at 15, the sides of the lower end of the cup proper being by such upward yielding across the transverse center of the fold-line 10, drawn from their original contact with the sides of the band 13, as shown in Fig. 5, the perpendicular end edges of the bottom of the cup still remaining, however, in close relation to said band. The initial transverse crease or indentation I give to the middle of the fold-line or crease 10 is very slight and not necessarily perceptible and its purpose is to create a slight weakness across the transverse middle of the crease 10 so as to make certain that when pressure is applied to the

opposite edges of the lower part of the cup 55 or to the band 13, the crease 10 will properly buckle upwardly, as at 15, and leave the opposite sides of the band expanded, as shown in Fig. 5, to support the cup. After the cup has been opened out or expanded, it 60 may be readily restored to its collapsed condition by slight pressure, between the thumb and fingers, applied to its opposite curved sides.

The band 13 not only serves to support 65 the cup in standing position but it also covers over the lower ends of the edge joints or seams of the sides 11, 12 and protects the same from being broken open by contact with other articles, as for example 70 when carried in a satchel or in the pocket.

I deem it of importance that the cup in its entirety should have as few pasted joints as possible and should be so made as to lie flat when not in use and be capable of standing on its lower end when expanded for use. In accordance with the construction hereinbefore described, there is a pasted joint along each perpendicular side edge of the cup, and the band 13 has its meeting ends 80 pasted together at one edge of the cup so as to form an endless band, which is held in position on the cup by being pasted along its upper edges thereto.

What I claim as my invention and desire 85 to secure by Letters Patent, is:

A flexible paper drinking cup comprising two sides of substantially equal proportions to lie flat and parallel with each other in the collapsed condition of the cup and connected along a fold line at their lower edges, and a band transversely encompassing the lower end of the cup and secured thereto, said band in the open condition of the cup affording a supporting base therefor and 90 the connecting fold-line of said sides being adapted to be pressed upwardly at its transverse center to create a transverse brace (15) maintaining said band in its expanded condition; substantially as set forth. 100

Signed at New York city, in the county of New York and State of New York, this 19th day of September A. D. 1910.

FRANK A. WEEKS.
